His attorney.

UNITED STATES PATENT OFFICE.

CLINTON O. HARRINGTON, OF EDGEWOOD BOROUGH, PENNSYLVANIA, ASSIGNOR TO THE UNION SWITCH & SIGNAL COMPANY, OF SWISSVALE, PENNSYLVANIA, A CORPORATION OF PENNSYLVANIA.

ADJUSTMENT OF ELECTRIC LAMPS.

1,330,702.

Specification of Letters Patent. Patented Feb. 10, 1920.

Application filed April 7, 1916. Serial No. 89,636.

To all whom it may concern:

Be it known that I, CLINTON O. HARRINGTON, a citizen of the United States, residing at Edgewood borough, in the county of Allegheny and State of Pennsylvania, have invented certain new and useful Improvements in Adjustments of Electric Lamps, of which the following is a specification.

My invention relates to improvements in 10 incandescent electric lamps.

In light signals comprising a lamp and means (such as a lens or a reflector or both) for projecting a beam of light from the lamp, it is usual to employ "concentrated filament" lamps for reasons of efficiency. This filament, which is usually in the shape of a spiral, must be located at a definite point with respect to the projecting means, this point usually being the focus.

One object of my invention is the provision of means for adjusting the location of the filament of each lamp with respect to the lamp base or other member of the lamp by which it is located in the light signal, so that the filament of the lamp occupies a definite position relative to said base or other locating member. Consequently, when such a lamp is secured in the light signal, its filament occupies a definite position with 30 respect to the projecting means of the light signal. By using correct proportions, this position of the filament may be made the focal point. It is apparent that any lamp correctly adjusted according to my invention, may be used in any signal of the same dimensions, without the necessity of adjusting the position of the lamp to bring the filament into the focus.

I will describe one form of apparatus, 40 and one method of using the same, both embodying my invention, and with them point out the novel features thereof in claims.

In the accompanying drawings, Figure 1 is a view showing, partly in elevation and 45 partly in section, one form of apparatus for supporting the bulb of an incandescent lamp. Fig. 2 is a view showing means for locating a filament in the bulb in a given position with relation to part of the apparatus shown in Fig. 1. Fig. 3 is a view showing means for attaching a base to the bulb in a given position with respect to the 50 filament.

Similar reference characters refer to similar parts in each of the several views. 55

Referring first to Fig. 1, the reference character 50 designates a base plate on which are mounted two vertical standards 51. Means are provided on this base for securing a lamp bulb to the base; as here shown, these means comprise springs 52 of the shape shown in the drawing mounted on plate 50 by screws 52^a. These springs are disposed equidistant from a vertical axis *a*—*b*, which is preferably midway between 60 standards 51. Although but two springs appear on the drawing, it is understood that several others are mounted on plate 50 in similar manner, so that when a lamp bulb 53 is inserted between them, they hold the 65 bulb firmly in place. The bottom of the bulb rests on a shoulder 57, a hole 57^a being provided in the base plate to receive the bulb tip. To bring the bulb into a substantially vertical position, I provide a member 70 75 56 which by suitable holes through its ends is adapted to slide vertically on standards 51. In its middle member 56 has a hole 55, part of which is of such diameter as to fit snugly over the neck 54 of the lamp bulb. Member 56 is slid downward on standards 80 85 51 until its shoulder 58 rests on the bulb surface. It is easily seen that the lamp bulb is now held in a position wherein its vertical axis substantially coincides with axis *a*—*b*. Furthermore, member 56 is located in a definite position with respect to the bulb surface or at least that portion thereof which is in contact with shoulder 58. If the filament is now secured to the 90 bulb so that it occupies a predetermined position with respect to member 56, it will also occupy a predetermined place in the lamp bulb.

To secure this result the glass stem 59 95 which supports the filament 60 in the usual manner is inserted into a vertical central hole through another member 61 (see Fig. 2) mounted like member 56 to slide on standards 51. The filament is adjusted 100 until it occupies a predetermined position with respect to member 61, this adjustment being made partly by bending the supporting wires 60^a of the filament, and partly by sliding stem 59 up or down in member 61. 105 A set screw 59^a may be used to hold the stem

59 in this position. When the filament has thus been brought into the desired position relative to member 61, this member is placed on top of member 56 as shown in Fig. 2, so 5 that the filament is then supported at a definite position relative to the lamp bulb. The filament is secured to the lamp bulb when in this position by fusing together the neck of the bulb and the stem 59 and then 10 removing the part of the stem extending beyond the neck of the bulb as is well understood by those versed in the art.

With the filament thus secured in a definite place in the bulb it is necessary only to 15 fasten a lamp base at a definite position thereon to secure a definite location of the filament with respect to the lamp base. Accordingly, the members 61 and 56 are removed from standards 51 and replaced by 20 similar third member 62 (see Fig. 3) which has a central hole for receiving a lamp base B of any suitable type. The base here shown comprises a metallic shell 64 one end of which is flanged to form a surface similar to shoulder 58 on member 56. This 25 flange rests on the part of the surface of the lamp bulb previously occupied by shoulder 58 on member 56, and consequently the filament which has been fixed in a definite position with respect to this part of the bulb, as 30 hereinbefore described, is also in a definite and predetermined position with respect to the lamp base.

The base may be secured to the lamp bulb 35 in a manner usual in the art. The base shown in the drawing comprises a glass disk 65 having a central hole for receiving a hollow metallic eyelet 66 through which one of the lead-in wires of the filament is drawn. 40 The other filament wire is threaded through a small hole in the shell 64. The shell is partly filled with cement in a plastic condition and then applied to the lamp bulb. It is then located thereon by means of member 62 and held in this position until the cement has set. Member 62 is then lifted off standards 51 and the lamp is withdrawn from the clamp. The lead-in wires are cut off to the required length and soldered at 45 50 their ends to eyelet 66 and shell 64 respectively.

Although I have herein shown and described only one form of apparatus embodying my invention and have explained only 55 one method embodying my invention, it is understood that various changes and modifications may be made therein within the scope of the appended claims without departing from the spirit and scope of my invention.

Having thus described my invention, what I claim is:

1. The method of accurately locating a lamp base with respect to the filament which 60 65 consists in securing the filament at a pre-

determined position with respect to the filament supporting member and fixing the lamp base on said filament supporting member at a predetermined position with respect thereto.

2. The method of accurately locating the lamp base of a lamp with respect to the filament of the lamp which consists in securing the filament in alinement with a filament supporting member and fixing the lamp base 75 to said filament supporting member in alinement with said member and at a predetermined distance from the filament.

3. The method of assembling an incandescent lamp which consists in clamping the 80 lamp bulb in a stationary supporting member, securing the filament in alinement with the filament supporting member, securing said filament supporting member in a predetermined position with respect to said 85 lamp supporting member, fusing said lamp bulb to said filament supporting member and securing the lamp base to said bulb at a predetermined position with respect to said lamp supporting member.

4. Apparatus for assembling incandescent electric lamps, comprising means for securing the filament at a definite position in the bulb, and means for securing the lamp base at a definite position on said bulb.

5. Apparatus for assembling incandescent electric lamps, comprising means for securing the filament in the bulb at a definite position relative to part of the bulb surface, and means for securing the lamp base at a definite position relative to said part of the bulb surface.

6. In combination, means for holding a lamp bulb, means for adjusting said bulb into a definite position in said bulb holding 105 means, said means comprising a member held in a definite position relative to a portion of the surface of said bulb, a member for temporarily supporting a lamp filament in a definite position, means for bringing said member into a definite position relative to said first-mentioned member when said filament is inserted into the bulb, means for securing the filament in the bulb in said position, means for adjusting the lamp base on 110 said bulb with respect to the said portion of the bulb surface and means for securing the base to the bulb in said adjusted position.

7. The method of assembling the parts of an incandescent lamp so that they bear a 120 definite relation to each other, which consists in clamping the lamp bulb in a support, adjusting the lamp bulb into a definite position on said support, securing the filament in a definite position relative to a temporary supporting member, bringing said filament supporting member into a definite position with respect to a portion of the surface of the bulb when said filament is inserted into said 125 bulb, securing the filament in said bulb, and 130

affixing a base to said bulb in a definite position relative to said portion of the bulb surface.

8. The method of assembling the parts of an incandescent lamp so that they bear a definite relation to each other, which consists in securing the filament in the bulb at a definite position with respect to part of the bulb surface, and fixing the lamp base

to the bulb in a definite position relative to 10 the same portion of the surface of the bulb.

In testimony whereof I affix my signature in presence of two witnesses.

CLINTON O. HARRINGTON.
